COMBINATION CHALKBOARD AND ERASER
RAIL OR SIMILAR ARTICLE

Pearl Raymond Windhorst, Oakland, Calif., assignor to American Seating Company, Grand Rapids, Mich., a corporation of New Jersey

Application December 16, 1948, Serial No. 150,190

Term of patent 14 years

(Cl. D25—1)

To all whom it may concern:

Be it known that I, Pearl Raymond Windhorst, a citizen of the United States, residing at Oakland, in the county of Alameda and State of California, have invented a new, original, and ornamental Design for a Combination Chalkboard and Eraser Rail or Similar Article, of which the following is a specification, reference being had to the accompanying drawing, forming a part thereof.

Fig. 1 is a front elevational view of a combination chalkboard and eraser rail or similar article, showing my new design;

Fig. 2 is a side elevational view thereof;

Fig. 3 is a top plan view thereof; and

Fig. 4 is a fragmentary cross-sectional view thereof, to an enlarged scale, of the eraser rail portion thereof, taken on line 4—4 in Fig. 1.

The combination chalkboard and eraser rail or similar article is partially broken away in Figs. 1, 2 and 3 for convenience of illustration.

I claim:

The ornamental design for a combination chalkboard and eraser rail or similar article, substantially as shown and described.

PEARL RAYMOND WINDHORST.
